FURNACE CONSTRUCTION

Louis H. Hosbein, Glencoe, Ill., assignor to M. H. Detrick Company, Chicago, Ill., a corporation of Delaware

Application October 8, 1934, Serial No. 747,317
Renewed October 26, 1937

32 Claims. (Cl. 110—99)

This invention relates to the construction of furnaces in which refractory blocks or tiles are used for forming portions of the furnace arches or walls. More particularly, it relates to furnace 5 arch construction and to tiles for the building of same.

One of the objects of the invention is the provision of an improved furnace arch construction, and tiles for the building of same, whereby dis- 10 integration of the arch by spalling will be in large measure avoided.

A principal object of the invention is to provide a furnace constructed of like refractories or tiles each having a body portion with offset 15 two-way anchoring means adjacent one end and face portions provided with complementary seats and projections symmetrically positioned on the faces with respect to the anchoring means to provide an interlock when corresponding faces of 20 tiles are placed together with the two-way anchoring means in alignment.

Another object is the provision of a furnace arch structure and a tile for building same, which will be effective to minimize spalling and where- 25 in but a single form of tile is required for the construction of an entire flat refractory arch or furnace wall.

Another object is the provision of a refractory furnace arch or wall construction, and an im- 30 proved refractory tile for building same, which will be effective to minimize air or gas leakage through the arch or wall.

Yet another object is the provision of an im- 35 proved radial or convex furnace arch or wall structure and improved refractory tiles for building same, which will be effective to minimize dis- integration of the structure by spalling.

Another object is the provision of an arch structure having the advantages above specified 40 and which can be assembled or erected or repaired with facility.

A further object is the provision of improved furnace tiles which are adapted for the building of furnace arch and wall structures having the 45 characteristics above specified, and which tiles may be manufactured with facility, particularly in machines of the type known as dry-presses.

Other and further objects of the invention will be pointed out or indicated hereinafter or will 50 be apparent to one skilled in the art upon an understanding of the invention or its employment in use.

For the purpose of aiding in an explanation of the invention, I show in the drawings forming 55 a part of this specification, and hereinafter de-

scribe, certain arch structures, and tiles of certain forms, which represent embodiments of the invention; but it is to be understood that these are presented merely for purpose of illustration and are not to be construed in any fashion such as to limit the appended claims short of the true and most comprehensive scope of the invention in the art, as I am aware that the invention may be embodied in various other particular forms of arch and wall structures and tiles. 10

In said drawings,

Figs. 1, 2, 3 and 4 are elevational views showing respectively four faces of a form of tile embodying the invention, Fig. 2 showing the face opposite to that shown in Fig. 1, Fig. 3 showing 15 the side face at the right hand side of Fig. 1, and Fig. 4 showing the side face opposite that shown in Fig. 3;

Fig. 5 is a sectional elevational view of a portion of a furnace arch made up of tiles of the 20 form illustrated in the preceding figures;

Fig. 6 is a bottom view of a portion of such arch structure;

Fig. 7 is a perspective view of a tile having a face of the form illustrated in Fig. 1 and its sides 25 of the forms illustrated in Figs. 4 and 3;

Fig. 8 is a perspective view of a slightly modified form of tile;

Fig. 9 is a side sectional elevational view of a portion of a radial or convex furnace arch struc- 30 ture;

Fig. 10 is a sectional view, on line 10—10, of the structure illustrated in Fig. 9; and

Fig. 11 is a perspective view of a wedge-shaped tile constituting one of the elements of the struc- 35 ture shown in Figs. 9 and 10.

Furnace arches and walls which are built up of refractory tiles are subject to disintegration through spalling, which results from the breaking off of portions of the tiles and the dropping 40 out of the broken-off portions. Such breaking of the tiles may occur as the result of stresses set up in the tiles themselves incident to their heating and cooling, and from pressures exerted by the tiles upon one another as the result of 45 their thermal expansion. When a broken portion of one tile falls out of the structure, it leaves side faces of other tiles exposed to the furnace fire and increases their susceptibility to spalling.

The present invention provides a refractory 50 furnace construction, and forms of tiles for building it, which will be effective to retain broken-off portions of tiles in the structure, so that they continue to function as effective portions of the refractory arch and deter its disintegration. The 55

invention also provides a refractory furnace structure having a desirable flexibility or mobility of the component tiles relative to one another, whereby the tiles are enabled to accommodate themselves to thermal expansion of the structure and avoid the imposition of breaking pressures upon one another. While obtaining this desirable flexibility in the structure, the invention provides for the effective joining of the juxtaposed tiles in a fashion such as to minimize leakage of air or gas between them.

The nature of the invention may be ascertained in more detail by consideration of illustrative embodiments which are shown in the drawings and which will now be described.

In Figs. 1 to 4 inclusive is illustrated one form of tile which may be employed for construction of an entire flat refractory arch or a furnace wall and also portions of a convex radial arch structure. For convenience of designation, I will refer to the broader lateral sides of this tile as "faces" and the narrower ones as "sides". The tile is designated generally by the reference numeral 14, and at a suitable distance from its upper or outer end it is provided with grooves 15a and 15b extending inwardly from its sides, to provide a head having overhanging shoulders 16a and 16b. The groove 15a is approximately twice the depth of the groove 15b, and while the shoulder 16b extends out to the adjacent side of the tile, the shoulder 16a is in-set from its side of the tile by a distance d substantially half the depth of the groove 15a. Thus, the width of the tile across the shoulders is less than the total width of the tile and the head is asymmetrically located with respect to the faces of the tile. The upper portions of the faces are formed as flat surfaces 17a and 17b and the upper portions of the sides as flat surfaces 18a and 18b, said surfaces being arranged in rectangular relationship. Below the flat surface 17a the face of the tile is provided with a series of parallel intra-marginal projections 19a interspersed by a series of parallel intra-marginal seats 20a, a series of short marginal projections 21a interspersed by a series of short marginal seats 22a, and a series of parallel marginal projections 24a interspersed by a series of parallel marginal seats 25a. The projections are all of the same width, and at their bases their width is the same as that of the bottoms of the seats. The sides of the projections are beveled, however, so that their crowns are narrower than the bottoms of the seats. Both ends of the projections 19a are beveled to a gentle slope, and the inner ends of the projections 21a and 24a are likewise beveled. The projections 21a and 24a are arranged in alignment with the seats 20a, and the projections 19a in alignment with the seats 25a. The projections extend outwardly somewhat beyond the flat surface 17a and the seats are depressed inwardly slightly beyond said flat surface. The total length of projections 19a is approximately equal to the combined total lengths of projections 24a and 21a and the length of projections 21a is somewhat less than distance d .

The side of the tile below the flat surface 18a (Fig. 4) is formed with a series of parallel projections 27a interspersed by seats 28a, said projections extending outwardly somewhat beyond the flat surface 18a and each merging at one end with a projection 21a and terminating at the other end at a seat 22b. The seats 28a are depressed inwardly somewhat beyond the surface 18a and at one end each merges with a seat 22a

and at the other with a projection 21b. The projections 27a are of the same width as projections 19a and 24a and seats 28a the same width as seats 20a and 25a. The projections 27a are beveled at their sides, so that while their bases are approximately the same width as the bottoms of the seats 28a, their crowns are narrower than said seats.

The opposite side of the tile (Fig. 3) below the flat surface 18b is provided with a series of projections 27b interspersed by seats 28b, said projections and seats being similar to projections 27a and seats 28a, but with the projections 27b opposite the seats 28a.

The face of the tile below the flat surface 17b (Fig. 2) is formed with a series of intra-marginal projections 19b similar to projections 19a, a series of intra-marginal seats 20b similar to seats 20a, a series of short marginal projections 21b similar to projections 21a, a series of short marginal seats 22b similar to seats 22a, a series of marginal projections 24b similar to projections 24a, and a series of marginal seats 25b similar to seats 25a. The projections and seats on one face are arranged in staggered relationship to the corresponding projections and seats on the other face, so that projections 19b are opposite seats 20a, seats 20b opposite projections 19a, projections 21b opposite seats 22a, seats 22b opposite projections 21a, projections 24b opposite seats 25a, and seats 25b opposite projections 24a. Consequently, the outer ends of projections 24b merge with ends of side projections 27b, and the outer ends of projections 21b terminate at the bottoms of seats 28a. All of the projections and seats extend transversely of the tile at right angles to the longitudinal median lines of its faces and sides.

A refractory tile of this construction is adapted to manufacture in a dry-press. As is known in the art, for the forming of refractories in a dry-press, the clays are prepared in a finely ground condition, but with a relatively small content of moisture, so that the mixture is not inherently cohesive or plastic. A suitable quantity of the more or less granular mixture is placed in a mould of the desired form and therein subjected to very high pressures such as to shape it accurately and closely to the mould matrix and cause it to cohere.

For the construction of a flat arch or suspended arch or furnace roof, it is customary to suspend the arch tiles from arch bars, hangers or other supporting members. The present invention provides an improved arch construction of this character. As seen in Fig. 5, the reference numeral 40 designates the lower portion of a suitable beam or similar member constituting a part of the arch supporting structure. There may be a plurality of such beams, and they may extend either transversely or longitudinally of the furnace. A plurality of arch bars or hangers 41 is supported from such beams, as by members 42, which permit the arch bars to be shifted toward and from one another, either by sliding or swinging movement or both. The tiles are supported on these arch bars or hangers by engagement of their shoulders 16a and/or 16b on the flanges thereof, and are arranged in courses. The tiles 14 are particularly qualified to be supported in pairs, viz., two tiles side by side, between adjacent arch bars, each tile engaging but a single arch bar, and thus avoiding multiplication of the arch bars. In Fig. 5 is shown portions of two courses of tiles, the courses running transversely of the

arch bars, tiles in the front course being shown at the left hand side of the figure and tiles in the rear course being shown at the right hand side of the figure. The tiles in the front course 5 are hung with their shoulders 16a at the left, while tiles in the rear course are hung with their shoulders 16b at the left. So hung, the juxtaposed tiles in the respective courses have their side projections and seats 21a, 28a, 27b and 28b 10 intermeshed. As observed in Fig. 6, in this arrangement of the tiles those of one course are offset laterally with respect to the courses which are in juxtaposition to them. In this relationship the tiles in one course have their projections 19a in the seats 25a of the tiles in one juxtaposed course and their projections 24b in seats 20b of the tiles in the other juxtaposed course. Likewise, the tiles in each course have their projections 24a in the seats 20a of the tiles in one 15 juxtaposed course and their projections 19b in seats 25b of the tiles in the other juxtaposed course. The shoulders of the tiles in all of the courses align longitudinally of the arch bars, the narrowed upper portions of the tiles over the 20 grooves 15a accommodating the webs of the arch bars. The short marginal projections 21a and 21b of the tiles in each course extend beyond the side joints between the tiles in the adjacent courses and occupy portions of the seats 20a and 25 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

gas through them is effectively baffled, despite the relative mobility of the tiles. Accordingly, sufficient latitude may be allowed in the joints for accommodation of thermal expansion of the tiles, and the imposition of breaking pressures of the tiles upon one another avoided.

It is furthermore to be observed that but a single form of tile is required for the building of the entire flat arch or roof and that with such single form of tile the roof may be constructed 10 with broken joints in both the longitudinal and transverse directions of the arch, as well as through the arch. In Fig. 8 is illustrated a slightly modified form of tile wherein the short marginal projections 21a and 21b are dispensed 15 with and the flat surfaces 17a and 17b continued down the marginal portions of the faces which were occupied by said projections in the form of tile above described. An arch structure as above described may be built with this form of tile throughout, and while the side joints may be staggered as above described, the portions of 20 the tiles which break the joint will not be intermeshed. In construction of an arch with tiles which have one face formed with the projections 25 and seats and the other face flat, the tiles are arranged in courses with the projections and seats of those in one course interfitting with the projections and seats of those in one juxtaposed course and with the flat faces abutting the flat 30 faces of the tiles in the other juxtaposed course.

The grooves 15a and 15b are of uneven length, while the shoulders 16a and 16b are of substantially even length, thereby providing a two-way suspension or anchoring means by which the tiles can be suspended from either side, as shown in Fig. 5. When the tile is suspended from the shoulder 16a the body portion of the tile extends further beneath the anchoring member 41 than when the tile is suspended from shoulder 16b. This offsets the anchoring or suspending means with respect to the faces of the tile and provides for overlapping of the tile as shown in Fig. 6. The projections 19a and the seats 25a are symmetrically positioned with respect to the anchoring means. Seats 20a and projections 24a likewise are on the same horizontal level and correspondingly positioned with respect to the median line of the anchoring means. On the opposite face of the tile the seats and projections are correspondingly positioned. In the embodiment of the tiles shown in Figs. 1 to 4 the second set of projections 21a and seats 22a are symmetrically positioned with respect to the ends of seats 20a and projections 19a, respectively, on that portion of the face of the brick which extends beyond the shoulder 16a. When two tiles are suspended with faces 17a positioned adjacent 17b by the offset anchoring means the seats of one face interlock with the projections of the other face, as shown in Fig. 6. This positional relationship of the seats and projections provides for the construction of an entire flat wall of identical tile and for anchoring or suspending the tile by the shoulders 16a and 16b.

In Figs. 9 and 10 is illustrated a convex radial arch construction in which tiles of a type above described may be employed in conjunction with a wedge-shaped tile such as illustrated in Fig. 11. This wedge-shaped tile is formed with its converging faces of but half the width of the tiles 14, and it is also somewhat shorter than said tiles. Preferably its larger end face is formed on a radius. Its sides are flat and parallel to each other, while one of its converging faces is formed 75

with a series of projections 51 interspaced by seats 52, said projections and seats extending transversely of the face and at right angles to the sides. The opposite converging face is formed with a similar series of projections 54 interspaced by seats 55. These projections and seats are of the same height, width and depth as the projections and seats of the tile 14, and the projections on one face are opposite the seats on the other face, and vice versa. The serial arrangement of the projections 51 corresponds to that of the seats 20a of tile 14 and the serial arrangement of projections 54 to that of seats 25a. In the radial arch structure, a plurality of the tiles 14 is suspended in an aligned series on a suitable bracket or arch bar in diverging relationship, and a pair of the wedge-shaped tiles 50 is disposed between each two of the tiles 14 in the series. One tile 50 of each such pair is disposed with its projections 51 in the seats 25b of one of the tiles 14 and its projections 54 in the seats 24a of the other tile 14. The other wedge-shaped tile 50 of the pair is disposed in reversed relationship, its projections 54 occupying seats 20b of the first mentioned tile 14 and its projections 51 occupying seats 20a of the other tile 14. As seen in Fig. 10, the outer sides of the tiles 50 thus arranged are offset with respect to the sides of the tiles 14, producing a broken joint arrangement. The short marginal projections 21a and 21b of tiles 14 are accommodated in seats 52 and 55 of the additional tiles 50 which are similarly arranged between other tiles 14 disposed collaterally with those of the first series. The lower ends of a series of the tiles 14 and 50 thus arranged, forms a convex radial arch surface. In this assembly, the tiles 50 are retained in the structure by their intermeshing engagement with the tiles 14. The structure has the desirable flexibility and accommodation for thermal expansion, and in addition to its provisions for the effective retention of broken tile fragments in the structure, is of particular advantage in permitting the use of tiles of quite small cross section without complication or multiplication of the metallic supporting members. The wedge-shaped tile 50 may be formed very easily and economically on a dry-press, the top and bottom mould members shaping the flat sides of the tile and the beveled ends of the projections 51 and 54 and the sides of the mould matrix shaping the projections and seats.

What I claim is:

1. A furnace arch structure comprising a plurality of refractory tiles each having a face formed with seats and projections in alternate arrangement both longitudinally and transversely thereof, said tiles being suspended by their upper ends in collateral and staggered relationship with said faces in approximately vertical position and with projections of respective tiles in seats of two other tiles which overlap the same side thereof.

2. A furnace arch structure comprising a plurality of refractory tiles each having a face formed with a plurality of projections and seats distributed alternately both longitudinally and transversely thereof, and means engaging said tiles at their upper ends to support them in depending position and collateral association with projections and seats of one tile intermeshed with seats and projections of another.

3. A furnace structure comprising a plurality of refractory tiles arranged in courses and each having a face formed with a plurality of narrow projections and seats arranged alternately in

rows both longitudinally and transversely thereof, the tiles in respective courses being disposed in staggered relationship to those in juxtaposed courses with said projections and seats of respective tiles of one course in interfitting relationship with seats and projections of like faces of a plurality of tiles of a juxtaposed course.

4. A furnace structure comprising a plurality of refractory tiles having each of two opposite faces formed with a plurality of both seats and projections arranged alternately in rows both longitudinally and transversely thereof and with the projections of one face opposite seats of the opposite face, said tiles being disposed with their like faces in juxtaposition and with projections and seats of respective tiles intermeshed with seats and projections of a pair of other tiles at each of opposite sides thereof.

5. A furnace structure comprising a plurality of identically shaped refractory tiles each having a face formed with a plurality of transversely extending narrow seats and projections in alternate arrangement both longitudinally and transversely thereof, said tiles being disposed with their ends in alignment and their like faces in juxtaposition and with projections and seats of respective tiles in meshing relationship with seats and projections of two other tiles at the same side thereof, and anchoring members retentively engaging outer end portions of some of the tiles.

6. A furnace structure comprising a plurality of refractory tiles having support-engaging portions adjacent their outer ends and having opposite faces formed with seats and projections in alternate arrangement both longitudinally and transversely thereof, anchoring members engaging said support-engaging portions, and a plurality of wedge-shaped tiles interposed between said first mentioned tiles with their narrower ends outward, said wedge-shaped tiles each having one of their converging faces formed with seats and projections intermeshing with projections and seat of one of said first mentioned tiles, whereby said wedge-shaped tiles are retained by and cooperate with said first mentioned tiles to form a convex arcuate refractory furnace portion.

7. A furnace structure as specified in claim 6 and wherein said wedge-shaped tiles are arranged in staggered relationship to said first mentioned tiles.

8. A furnace structure as specified in claim 6 and wherein the width of the converging faces of said wedge-shaped tiles is approximately one-half the width of the juxtaposed faces of the first mentioned tiles.

9. A furnace arch structure comprising a plurality of identically shaped refractory tiles each having two opposite faces formed with seats and projections in alternate arrangement both longitudinally and transversely thereof, said tiles being disposed in courses with the tiles of one course staggered with respect to those in juxtaposed courses, the seats and projections of tiles of adjacent courses being disposed in intermeshing relationship.

10. A furnace arch structure comprising arch bars disposed collaterally in spaced relationship and supported for shifting movement toward and from each other, and refractory tiles supported on said arch bars in courses running transversely thereof, each tile having supporting engagement with but a single arch bar and the center-to-center spacing of the arch bars being approximately equal to the width of two of the tiles, the tiles having their opposite sides each formed with

1. A plurality of narrow projections and seats arranged alternately in a series starting at the end of said side and running lengthwise thereof, said projections and seats of respective tiles being disposed in intermeshing relationship with those of the juxtaposed tiles in the same course at locations approximately opposite the arch bars and at locations approximately midway between the arch bars.
2. A furnace tile consisting of a block of refractory material primarily of rectangular cross section and having one of its lateral faces formed with shallow projections and seats in alternate arrangement both longitudinally and transversely thereof, the seats being of width to accommodate the projections, said tile being formed at its outer end with a support-engaging portion whereby it may be anchored with said lateral face in contact with the similar face of an identical tile and with the inner ends of the two tiles in the same plane and projections and seats of the two tiles in intermeshing relationship.
3. A tile for furnace construction, consisting of a block of refractory material having a support-engaging portion adjacent one of its ends and a lateral face formed with a plurality of series of shallow projections and seats, said series running longitudinally of the block and the projections in one series being staggered relative to those in another and the seats in one series being staggered relative to those in another, the seats in one series being of size and shape to receive projections corresponding to those in another series, whereby a plurality of such tiles may be disposed in lateral contact with their support-engaging portions in alignment and with projections and seats of their like faces in intermeshing relation.
4. A tile for furnace construction, consisting of a block of refractory material primarily of quadrangular cross section and formed with a support-receiving notch adjacent one of its ends, said block having one of its lateral faces formed with a plurality of projections and seats arranged alternately in rows both longitudinally and transversely thereof, the seats being of size and shape appropriate to receive the projections, and the support-receiving notch being offset laterally from the median line of said face, whereby a plurality of such tiles may be disposed in collateral overlapping relationship with their support-receiving notches in alignment and with projections and seats of their like faces in intermeshing relationship.
5. A tile for furnace construction comprising a block of refractory material primarily of quadrilateral cross section and having shoulders at opposite sides adjacent one of its ends, the shoulder at one side being in-set to a greater distance than that at the opposite side, said block having a lateral face formed with projections and seats distributed over the greater part of its area and arranged alternately both longitudinally and transversely thereof, the seats being of size and shape appropriate to receive the projections, whereby a plurality of such tiles may be anchored by their shoulders in collateral overlapping association with their shoulders in alignment and with projections and seats of their like faces in intermeshed relationship.
6. A tile as specified in claim 1 and wherein the surface of the upper portion of said face is flat and lies in a plane located outwardly from the bottoms of the seats and inwardly from the crests of the projections.
7. A tile for furnace construction consisting of a refractory block of primarily quadrilateral cross section and having a support-engaging portion at one of its ends, said support-engaging portion being in-set to a greater distance from one side of the block than from the other, said block having a lateral face formed with longitudinally running series of transversely extending seats and projections, the inner ends of the projections in respective series being in alignment longitudinally of the block and being beveled, the seats of one series being in alignment transversely of the block with the projections of the adjacent series, and the crests of the projections being somewhat narrower than the bottoms of the seats.
8. A tile as specified in claim 7 and wherein the opposite sides of the block are formed with projections and seats extending transversely thereof, the seats on each side being opposite to the projections on the other, the projections being narrow and the seats being of a width sufficient to receive the opposite projections.
9. A tile for furnace arch construction consisting of a refractory block of primarily quadrilateral cross section, said block having a lateral face formed adjacent its side margins with projections arranged in series running longitudinally thereof and with the projections in each series interspaced by seats, the projections in one series being aligned transversely of said face with those in the other series but being spaced therefrom by intervening seats; the transversely aligned projections being of like width longitudinally of said face and the seats being of width appropriate to receive the projections; said block being formed at one end with a support-engaging portion disposed asymmetrically of said face.
10. A tile as specified in claim 9 and in which the length of each of said intervening seats is at least as great as the combined length of the marginal projections between which it is interposed.
11. A tile for furnace construction consisting of a refractory block formed adjacent one of its ends with a portion for engaging an anchoring member, said block having opposite faces each formed with a multiplicity of shallow projections and seats arranged alternately in a plurality of series starting at the opposite end of the block and running longitudinally of said face, the projections in adjacent series being in staggered relationship, the seats of one series being of size to accommodate the projections of another series, and the extent of each projection and seat in the directions longitudinally of said face being but a very small fraction of the total length of the face.
12. A refractory furnace tile as specified in claim 11 and wherein said faces of the block adjacent said first mentioned end are flat and lie in planes outwardly beyond the bottoms of the seats and inwardly from the crests of the projections.
13. A refractory furnace tile as specified in claim 12 and wherein the opposite sides of the block are formed each with a series of transversely extending projections and seats disposed alternately, the seats on each of said sides being opposite the projections on the other and being of form complementary thereto.
14. A tile for construction of furnace arches and walls, comprising a refractory block of primarily quadrilateral cross section having each of two opposite faces formed with a plurality of longitudinally running series of projections which diverge abruptly from the normal surface planes.

of said faces, the sides of the projections forming sides of seats which are disposed alternately with the projections in the series, the projections in juxtaposed series being in staggered relationship and seats and projections in different series being aligned transversely of said faces so that the ends of projections form the ends of seats so aligned with them, the seats being of width sufficient to accommodate projections of 10 adjacent tiles corresponding to those which are aligned with said seats, and the block being formed at one end with a portion for retentive engagement with an anchoring member.

24. A furnace tile as specified in claim 23 and 15 wherein said series of projections and seats begin at one end of said faces and occupy the greater portion of the length of said faces.

25. A furnace tile as specified in claim 23 and 20 wherein each of the opposite sides of the block is formed with a longitudinally running series of 25 transversely extending projections interspaced by seats, the seats on each of said sides being opposite projections on the other of said sides and being respectively of size such as to accommodate the opposed projection of a similar adjacent tile.

26. A furnace construction, comprising spaced 30 anchoring members, and a plurality of courses of like refractory tiles extending transversely of said anchoring members, said tiles having two-way anchorage elements at one end engaging said anchoring members in alternate directions, the longitudinal median line of the anchorage elements of said tiles being offset with respect 35 to the longitudinal center line of said tiles, each tile having a projection on its face on one side of said longitudinal median line and a corresponding seat on the other side thereof, the longitudinal positions of said projection and seat relative to the anchorage elements being the same 40 and their positions with respect to said longitudinal median line being the same, the tiles in alternate courses being reversed to provide broken joints and to present like faces of said tiles in 45 contact, and the projections on the faces of said tiles engaging the seats on the tiles of the adjacent courses.

27. A furnace construction, comprising spaced 50 anchoring members, a plurality of courses of like refractory tile anchored to said anchoring members so that the joints in adjacent courses are staggered, said tiles being substantially identical and each having a two-way anchorage member offset so that its longitudinal median line is 55 spaced laterally from the center line of the tile, and a plurality of corresponding projections and seats on each of opposite faces of the tile symmetrically positioned with respect to said longitudinal median line, the tiles in adjacent courses 60 being mounted to said anchoring members in laterally reversed positions and the seats of each of said tile being in engagement with the projections on the like faces of the tiles in the adjacent courses.

65 28. A tile for furnace construction, compris-

ing a refractory block having opposite faces each divided into a main section and a laterally offset section, each of said main sections having a plurality of projections and corresponding seats on opposite sides of its longitudinal center line, 5 the corresponding projections and seats being in alignment transversely of the face and their spacing with respect to said center line being the same, and a two-way anchorage portion at the end of said main sections and shaped to engage 10 said tile with an anchoring member with said offset section positioned in either lateral direction but with the main sections in the same location relative to the anchoring member.

29. A furnace arch, comprising spaced anchoring members, and a plurality of courses of tile of the type described in claim 28 supported thereon, the tile in adjacent courses having their offset sections oppositely directed to provide broken joints, the seats of said main sections engaging 20 the projections of the main sections of tile in adjacent courses and the offset sections of tile in adjacent courses overlapping one another.

30. A tile for furnace arch construction, comprising a refractory block having opposite faces and a two-way suspension member at one end thereof for supporting said tile eccentrically, each of said faces having a plurality of corresponding projections and seats on opposite sides of the longitudinal center line of said suspension member, the longitudinal positions of corresponding projections and seats with respect to the longitudinal center line of the suspension member being the same and their spacing with respect to said center line being equidistant. 35

31. A tile for furnace arch construction comprising a refractory block having a suspension portion at the end thereof shaped for two-way securement to a support member, the vertical median line of said suspension portion being 40 offset laterally with respect to the vertical center line of said block, a vertical series of alternating transverse ribs and seats on each face of said block with the ribs and seats extending from adjacent the vertical median line of the suspension portion to the lateral margin of said block, and a vertical series of transverse seats and ribs 45 symmetrically positioned with respect to said series of ribs and seats on the other side of said median line of the suspension portion, the seats of each of said series being transversely opposite the ribs of the other of said series. 50

32. A tile for furnace construction, comprising a refractory block having a body portion with a suspension portion at one end thereof, the longitudinal median line of said suspension portion being laterally offset with respect to the longitudinal center line of said body portion, and said body portion being provided with a projection on one side of said longitudinal median line and a 55 corresponding seat on the other side thereof, said projection and seat being equidistantly positioned with respect to said longitudinal median line along a line perpendicular thereto. 60
